Attorneys.

UNITED STATES PATENT OFFICE.

JOHN J. OWENS, OF BLACKSBURG, VIRGINIA.

GLASS-WASHING BASKET.

Application filed January 14, 1922. Serial No. 529,299.

To all whom it may concern:

Be it known that I, JOHN J. OWENS, a citizen of the United States, residing at Blacksburg, in the county of Montgomery 5 and State of Virginia, have invented certain new and useful Improvements in Glass-Washing Baskets; and I do hereby declare the following to be a full, clear, and exact description of the invention, such as will 10 enable others skilled in the art to which it appertains to make and use the same.

This invention relates to new and useful improvements in washing machines and more particularly to what will be known as 15 a washing basket, the main object of the present invention being the provision of a basket or receptacle for the purpose of containing a plurality of glasses and articles of a like character for washing and sterilizing 20 purposes.

Another object of the present invention is the provision of a washing basket wherein a plurality of glasses or similar articles may be placed therein and so arranged that when 25 the basket is dipped into the washing or sterilizing fluid, the contents of the basket may be quickly and readily cleansed or sterilized and the articles contained within the basket are so arranged that the fluid in 30 which they are submerged will reach every part of each individual article, thus assuring of the proper cleansing or sterilizing of each article.

A further object of the invention is the 35 provision of a glass washing basket so constructed and arranged and provided with suspension means whereby the basket can be used in connection with a well known washing machine in use at the present time 40 and wherein the glasses or other articles can be quickly and readily placed in position within the basket or removed therefrom.

With the above and other objects in view the invention consists in the novel features 45 of construction, combination and arrangement of parts hereinafter more fully set forth, pointed out in the claim and shown in the accompanying drawings, in which:

Figure 1 is a front elevation of a washing 50 basket constructed in accordance with my invention;

Fig. 2 is a side elevation, and

Fig. 3 is a top plan view.

In carrying out the invention, the main 55 body of the basket is formed first by provid-

ing the rectangular end portions 1, said end portions being formed of bars or strips of metal preferably cylindrical and bent to form the rectangular frames. These frames are suitably connected by means of diagonally extending wire braces 2 and 3 arranged in plurality throughout the side and end walls of the basket. It will be noted that the bracing wires 2 are fastened at one end to one of said frame members and extend in a diagonal line to the other of said frame members and secured thereto. The bracing wires 3 are secured in the same manner but extend on a diagonal line in a direction opposite from the bracing rods 2. Attention 70 is also called to the fact that these brace rods 2 and 3 while extending between the two frame members 1 are alternately extended over and under the opposing rods, the brace rods 2 being extended over and under alternate rods 3 so as to form a continuous mesh throughout the side and end portions of the basket. 75

The bottom of the receptacle is formed by extending transversely thereacross in opposite directions a plurality of double rods 4, the ends of which are bent around the side portions of the frame 1 and thus securely held in place. The top which normally closes one side of the basket is formed of a single strip of metal bent upon itself upon opposite sides of the center to form the projections 5 which normally rest, when in a closed position, against one side portion of one of the frames 1. The ends of the strip 80 are then extended in parallel relation and provided with loops 6 adapted to embrace the opposite side portion of the frame 1 whereby the frame 7 of the cover will be hingedly connected to the body of the basket. 85

The ends of the strip which form the frame 7 are connected adjacent the loops 6 by means of a transverse connecting rod 8, the ends of which are bent upon themselves to form loops 9 embracing the side portions of the frame 7 adjacent the loops 6 whereby to provide a substantially rectangular frame for the cover of the basket. In order to provide means for forming a 100 complete cover, suitable double strands 10 of heavy wire are extended transversely between the side portions of the frame 7 formed by the ends of the first rod and the connecting rod 8. These double strands are 105 110

interengaged with each other at intervals so as to provide a woven center for the top or cover member. 35

In order to suspend the basket, within a ⁵ receptacle containing water for washing purposes or a sterilizing fluid, the frames 1 are connected upon opposite sides thereof by means of a rod 11, the ends of which are looped upon the frames 1 while the intermediate portion thereof is formed into an eye 12 through which the ends of the bail 13 extends, said bail being arranged at one ¹⁰ end of the basket and provided with a roller 14 adapted to be engaged by a hook, cable or other supporting means. It will be noted that the ends of the bail 13 are mounted within the eyes 12 for pivotal movement whereby the bail may be dropped downwardly onto the ends of the basket when not in use. 40

In order to provide for proper closing for the cover member, a plate 15 is secured to the cover member and provided with a loop 16 and a hasp 17 is pivotally connected ²⁵ with one of the frames 1 and adapted to engage over the loop 16 while a hook member 18 is engaged with the loop 16 to retain the hasp in position and hold the cover member in a normally closed position. 45

As illustrated in the drawings, two layers of glasses or other similar articles may be arranged within the basket, said layers being divided by means of the partition plate 19, said plate having a plurality of 50

perforations 20 to permit a thorough circulation of the water between the two halves of the basket. 55

From the above taken in connection with the accompanying drawings, it will be readily apparent that I have provided an improved basket or receptacle for the purpose of containing glasses or similar articles whereby the basket or receptacle may be suspended and submerged into a washing or sterilizing fluid and the fluid reach all parts of each individual article. The articles are so arranged within the receptacle or basket whereby to permit a thorough circulation of the fluid within the basket so that the washing or sterilizing operation may be readily carried out. The device as a whole can be used individually or with a well known make of dish washing machine in use at the present time. 60

I claim:

The combination with a dish washing basket, of a top or cover portion adapted to close one side of the basket when in a normal position, and being hingedly connected to the basket at one edge, of means for suspending the basket, comprising a bail member arranged at one end of the basket, the said bail member provided with a roller adapted to be engaged by a supporting means. 65

In testimony whereof I affix my signature.

JOHN J. OWENS.
